UNITED STATES PATENT OFFICE.

JOHN T. DANIELS, OF NEWARK, NEW JERSEY, ASSIGNOR OF ONE-HALF TO THE HANSON & VAN WINKLE COMPANY, OF NEWARK, NEW JERSEY, A CORPORATION OF NEW JERSEY.

ELECTROPLATING APPARATUS.

No. 901,280.

Specification of Letters Patent. Patented Oct. 13, 1908.

Application filed May 11, 1908. Serial No. 432,071.

To all whom it may concern:

Be it known that I, JOHN T. DANIELS, a citizen of the United States, and a resident of the city of Newark, county of Essex, and 5 State of New Jersey, have invented certain new and useful Improvements in Electroplating Apparatus, of which the following is a specification, reference being had to the accompanying drawings, in which—

10 Figure I is a central vertical section; Fig. II a detail on enlarged scale; Fig. III a perspective view from direction of arrow on Fig. I, part on line $a-a$ being shown in section; Fig. IV a detail on enlarged scale end 15 view of container some parts shown as broken away; Fig. V a detail on enlarged scale showing the cathode; Fig. VI and VII details on enlarged scale of oscillating cam.

The object of my present invention comprises increased facility, rapidity, control, 20 economy and efficiency in the art of electroplating, and polishing, small articles in mass. I have found that in this art, it is of advantage that the mass, or units, of the articles treated in containers may be positively 25 forced not only by gravity but also, when required, by centrifugal pressure against the cathode and against each other to intensify electrical contact, also that a relatively large 30 volume of electrolytic solution be employed, also that the range of movements imparted to the articles during treatment be as extended as possible, also that those portions 35 of the solution in proximity to the anodes be kept comparatively stationary, while those portions within the container and in proximity to the articles or cathode be agitated and forced to circulate and issue from the container as much as possible, also that facilities be afforded for more conveniently and 40 entirely than heretofore removing the articles from the solution and its proximity, also from their container, and for altering, automatically or at will, and without interfering 45 with their tumbling, the depth of immersion of the articles in the solution.

I attain the aforesaid objects and advantages by my said improvements, which comprise, in their broadest aspect, the use of 50 a stationary tank containing a normally stationary electrolytic solution, a rotatable container permeable by the solution and detachably suspended therein from above by a single support or bearing, means to rotate

the said container in the solution on an 55 axis at an angle to the level of the surface of the latter, stationary anodes in said solution outside of said container, a cathode within and preferably at the bottom of said container, means to oscillate the said 60 container in a plane at an angle to the surface level of said solution, and also the imparting to said container of a downwardly flared, or truncated cone, shape, thus imparting thereto a relatively expanded bottom, of greater area than said cathode, whereby relatively greater centrifugal pressure is applied to parts of the solution within the container in proximity to the cathode and the articles, resulting in a more positive 70 flow of the solution through the container.

Referring now to the drawings, 1 is the tank of wood, or other non-conducting material, containing an electrolytic solution, the level, or upper surface of which may be indicated, in the present instance, by the line $a-a'$. 2, 2, are contact rods secured to said tank by means of straps 3, 3. 4, 4, are binding posts secured to said contact rods and electrically connected by conductor wire 80 5. By means of the binding post 6 one of said contact rods 2 is connected, by the conductor wire + with the positive pole of a source of electrical energy.

7, 7, are anodes suspended in the solution 85 from rods 3.

8 is a container, in this instance and preferably, of approximately truncated cone shape, having through its sides perforations 9, 9, permeable by the solution. At the bottom, or enlarged end, of container 8 is located the metallic conductive cathode 10, concentric with metallic conductive shaft 11, to which it and container 8 are secured and thereby suspended. Preferably wooden, 95 non-conducting means as spider 12 are secured to shaft and container to increase their rigidity of connection. The cathode 10 is preferably, as shown, of less area than the expanded end, or bottom, of the container 100 upon which it is disposed, and extends radially in a plurality of directions from the center of said shaft. The bottom and sides of the container are composed of insulating material as for instance wood or celluloid, 105 or both. The shaft above the cathode is covered by insulating material, as by wooden sleeves 13, 13, or the like. The cathode is

preferably provided with radial, inwardly projecting ribs 14. 15 is a non-conducting handle swiveling on shaft 11.

Means for rotatably and removably sus-

- 5 pending the container from one side in said solution are provided as follows:—In brackets 16, secured to one side of tank 1, is journaled driving shaft 17, carrying sprocket wheel 18, or other means for applying power.
- 10 Collars 19 prevent shaft 17 from moving longitudinally. Secured upon shaft 17 is worm-gear 20. Loosely mounted on shaft 17 is a frame comprising conductive cross-bar 23, which connects conductive side-arms
- 15 22, 22, from which extend downwardly non-conductive or insulated arms 24, in which is loosely journaled shaft 17, such connection permitting said frame to be, to an extent, oscillated upon said shaft. One of said
- 20 side-arms 22 carries a perforated ear 25, the other a pair of perforated ears 26, in which is journaled a screw-shank 27 carrying a thumb-nut 28. A yoke 29 is by the bolt 30, pivotally connected at one end with per-
- 25 forated ear 25. The opposite end of said yoke is provided with a slot into which screw-shank 27 may be turned and the yoke secured in closed position as shown in Figs. II and III by turning down thumb-nut 28.
- 30 Cross-bar 23 carries a pair of upwardly extending lugs 31, adapted to receive and hold rotatably between them shaft 11 and its appurtenances. Secured to shaft 11 is worm-wheel 32, adapted to intermesh with worm-
- 35 gear 20 and having hub 33, with annular groove 34 containing anti-friction balls 35. Loosely mounted on shaft 11 is conducting collar 36 with annular flanges 37, 37'. To shaft 11 is secured sleeve 38 having annular groove containing anti-friction balls 39, said sleeve comprising cam 43 rotatable with said shaft on cam bearing 44.
- 40, 40, Figs. II and I are adjusting and supporting screws threaded into side-arms
- 45 22. The free ends of said screws may bear if required against top of one side of tank 1 and support, and limit the downward movement of, said frame and the shaft 11 suspended therefrom and container 8. One of
- 50 the side arms 22 of said frame carries a binding-post from which conducting wire 42 connects with the negative pole of the source of electrical energy.

The operation is as follows.—The container

- 55 with its appurtenances being isolated from the remainder of the apparatus is at any convenient place charged with the articles to be electroplated and simultaneously polished by "tumbling" therein. It is then brought to
- 60 the tank previously charged with a suitable electrolytic solution, and is suspended in latter by inserting collar 36 between lugs 31 and closing yoke 29. This brings sprocket-wheel 18 and worm-gear 20 into operative correlation, and, power being applied to driving
- 65

shaft 17, shaft 11, and thus the container, are rotated in the solution around an axis at an angle to the level of the surface of latter, whereby the articles are tumbled, and, the current being turned on, electroplated. Cam 43 at each revolution raises and alternately lowers shaft 11 relatively to cam bearing 44 thereby raising and lowering the contained articles relatively to said solution, thereby oscillating the container and the articles in the solution in directions angular to those in which they are simultaneously rotated. Said oscillation also drives the articles by centrifugal force against the cathode and against each other compacting the mass, thus advantageously increasing perfection of contact and speed and efficiency of polishing, and it also positively forces solution out of the container through the apertures located in the sphere of the greatest centrifugal action, and causes intake of solution through those apertures where the centrifugal force is less, thus insuring when desired, and without interrupting operations, change and renewal of the solution within the container.

Whenever desired the container and its contents may, by opening yoke 29, and lifting out, be removed from the tank and its vicinity, and another like container and charge immediately substituted and the tank and its solution thus utilized continuously. The relative expansion of the bottom of the container, insures desirable greater agitation of the solution and the articles proximately to the cathode; also greater centrifugal pressure near the cathode thus assisting removal of stale solution from its vicinity, and also the concentric cathode of less area than said bottom, assures desirable constant covering of the cathode by the solution and by the articles. The obliquity of the rotation of the container relatively to the solution contained in the stationary tank also desirably increases the agitation of the solution proximately to the articles and its permeation and circulation in and out of the container. The radial blades on the cathode as disposed desirably increase the agitation of the articles and the outflow of the solution from their vicinity.

The oblique suspension of the container as described, and its removability from the solution, and from proximity to the tank, facilitate and improve electroplating and result in numerous economies.

I am aware that it has been heretofore suggested that oscillatory tanks, or barrels containing electrolytic solutions for electroplating be rotated on an inclined axis to cause tumbling of the articles under treatment, also that such barrels have contained baskets or the like to contain said articles, such baskets being secured to and rotating with said barrels, and I do not wish to be understood as claiming any such devices, which are broadly distinguishable from my present

improvements in that the said barrels and their contents being supported pivotally upon a sub-disposed base, instead of being suspended like my container, their oscillation results only in undesirably forcing the articles centrifugally out of contact with the cathode and with each other, the reverse being the case in my novelly suspended container, and besides in the case of the said 5 barrels, the articles are not rotated in a solution contained in a stationary tank. I am also aware that articles have been heretofore tumbled in drums rotated in stationary tanks containing a solution, but in these instances 10 the drums have been rotated on non-oscillatory horizontal shafts or axes, precluding my said arrangement of cathode, and above described effects of my apparatus upon the solution and articles, nor do I claim any 15 such devices.

What I claim as new and desire to secure by Letters Patent is the following, viz:—

1. An electroplating apparatus comprising a stationary tank containing an electrolytic solution, a permeable container suspended from one side in said solution and rotatable therein on an axis at an angle to the level of the surface of said solution, means to rotate said container on said axis, an 20 anode in said solution outside of said container, and a cathode within said container.

2. An electroplating apparatus comprising a stationary tank containing an electrolytic solution, a permeable container suspended from one side in said solution and rotatable on an axis at an oblique angle to the level of the surface of said solution, means to rotate said container on said axis, an 25 anode in said solution outside of said container, and a cathode within said container.

3. An electroplating apparatus comprising a stationary tank containing an electrolytic solution, a permeable container suspended from one side in said solution and 30 rotatable on an axis at an angle to the level of the surface of said solution, means to rotate said container on said axis, an anode in said solution outside of said container, and within said container a cathode concentric 35 with said axis and extending radially in a plurality of directions therefrom.

4. An electroplating apparatus comprising a stationary tank containing an electrolytic solution, a permeable container suspended from one side in said solution and 40 rotatable on an axis at an angle to the level of the surface of said solution, means to rotate said container on said axis, a stationary anode in said solution outside of said container, and within and constituting part of 45 the inner surface of said container a cathode concentric with said axis and extending radially in a plurality of directions therefrom.

5. An electroplating apparatus comprising

ing a stationary tank containing an electrolytic solution, a permeable container suspended from one side in said solution and rotatable on an axis at an angle to the level of the surface of said solution, means to rotate 70 said container on said axis, an anode in said solution outside of said container, and within and at the bottom of said container, a cathode extending radially from said axis.

6. An electroplating apparatus comprising a stationary tank containing an electrolytic solution, a permeable container suspended from one side in said solution and rotatable on an axis at an angle to the level of the surface of said solution, means to rotate 75 said container on said axis, an anode in said solution outside of said container, and within and on the bottom of said container, a cathode concentric with said axis.

7. An electroplating apparatus comprising a stationary tank containing an electrolytic solution, a permeable downwardly expanded container suspended from one side with its base downwards in said solution, 80 rotatable on its own central axis at an angle to the level of said solution, means to rotate said container on said axis, an anode in said solution outside of said container, and within and on the base of said container a cathode.

8. An electroplating apparatus comprising a stationary tank containing an electrolytic solution, a permeable downwardly expanded container, suspended from one side with its base downwards in said solution, 85 rotatable on its own central axis at an angle to the level of the surface of said solution, means to rotate said container on said axis, an anode in said solution outside of said container, and within and on the base of said 90 container a cathode concentric with, and of less area than said bottom.

9. An electroplating apparatus comprising a stationary tank containing an electrolytic solution, a permeable downwardly expanded container, suspended from one side with its base downwards in said solution rotatable on its own central axis at an angle to the level of the surface of said solution, 100 means to rotate said container on said axis, a stationary anode in said solution outside of said container, and within and on the bottom of said container a cathode concentric with, and of less area than said base, 105 and means to insulate from said solution all connections with said cathode.

10. An electroplating apparatus comprising a stationary tank containing an electrolytic solution, a permeable container suspended from one side in said solution and 110 rotatable on an axis at an angle to the level of the surface of said solution, means to rotate said container on said axis, an anode in said solution outside of said container, a 115 cathode within said container, and means to 120

125

130

raise and lower said container relatively to said solution.

11. In an electroplating apparatus comprising a cathode, an anode, and a tank containing an electrolytic solution, a permeable container, means to suspend said container from one side thereof, and means to oscillate said container in a plane projected at an angle to the horizon.

10 12. In an electroplating apparatus comprising a cathode, an anode, and a tank containing an electrolytic solution, a permeable container, means to suspend said container from one side thereof, means to oscillate said container in a plane projected at an angle to the horizon, and means to rotate said container around an axis projected at an angle to the horizon.

13. In an electroplating apparatus com-

prising an anode and a tank containing an electrolytic solution, a permeable container containing at its lower end a cathode, means at its opposite end to suspend said container and means to oscillate said container in a plane projected at an angle to the horizon. 25

14. In an electroplating apparatus comprising an anode and a tank containing an electrolytic solution, a permeable container containing at its lower end a cathode, means at its opposite end to suspend said container, means to oscillate said container in a plane projected at an angle to the horizon, and means to rotate said container around an axis projected at an angle to the horizon. 30
